UNITED STATES PATENT OFFICE.

ALFRED L. KRONQUEST, OF CHICAGO, ILLINOIS, ASSIGNOR, BY MESNE ASSIGNMENTS,
TO CONTINENTAL CAN COMPANY, INC., A CORPORATION OF NEW YORK.

CAN-END-FEEDING DEVICE.

1,148,175.

Specification of Letters Patent. Patented July 27, 1915.

Application filed June 3, 1912. Serial No. 701,362.

To all whom it may concern:

Be it known that I, ALFRED L. KRONQUEST, a citizen of the United States, residing at Chicago, in the county of Cook, State 5 of Illinois, have invented certain new and useful Improvements in Can-End-Feeding Devices, of which the following is a description, reference being had to the accompanying drawing and to the figures of reference 10 marked thereon.

The invention relates to new and useful improvements in feeding devices for delivering can ends one at a time to a seaming mechanism.

15 An object of the invention is to provide means for accelerating the travel of the ends after they are released from the stackholder, whereby the rapidity with which the ends are fed from the stackholder to the operating devices therefor may be increased.

20 A further object of the invention is to provide means located between the operating devices for the can ends and the stackholder for yieldingly engaging and conveying the 25 ends through the chute which leads to the operating devices, whereby the ends are forced through the chute.

These and other objects will in part be obvious, and will in part be hereinafter more 30 disclosed.

In the drawings which show by way of illustration one embodiment of the invention,—Figure 1 is a front view of a seaming machine having my improved feeding device 35 applied thereto; Fig. 2 is an enlarged detail, partly in section, showing the feeding device in side elevation; Fig. 3 is a detail view taken from the opposite side of the feeding device; Fig. 4 is a rear view of the feeding 40 device; and Fig. 5 is a detail showing the releasing member for the stackholder.

In the seaming of can ends on to the can bodies, it has been customary to feed the ends from a stackholder to the seaming devices. In such machines, the stackholder is 45 usually placed above the seaming devices, so that the can ends may drop by gravity when released from the stackholder into the seaming station. Considerable trouble has 50 been experienced in machines of this charac-

ter, in that the action of gravity upon the can ends is not sufficiently rapid to carry the can end to the seaming station. This is more especially true where can ends are fed to a multiple seaming machine having a plurality of continuously operating seaming stations. 55

In order that the travel of the can ends from the stackholder to the seaming station may be accelerated and the ends carried to 60 the seaming station and delivered thereto, as the seaming station passes by the chute for the can ends, I have provided devices for engaging the can ends as they leave the stackholder, for positively accelerating the 65 speed of the can ends, and for forcing the same through the delivering chute to the seaming station.

Referring more particularly to the drawings, I have shown in Fig. 1 a seaming machine consisting of a supporting base 1, on which is mounted a rotating carrier 2, which is provided with a plurality of rotating chucks 3 and seaming rollers which coöperate with the rotating chucks. This rotating carrier carries the seaming rollers and chucks past a receiving point where can bodies and can ends are fed to the seaming station. The carrier rotates continuously 70 and the end is double-seamed on to the can 75 body during the travel of the carrier. These parts are of the usual construction, and will not require further description.

The can bodies are fed from a chute 4 to the seaming stations. The can ends are 80 stacked in a stackholder 5. The can ends in the stackholder rest on a tapered ledge 6 at one side, and on a rotating releasing wheel or segment 7 at the other side. 85

The releasing wheel 7 is carried by a vertical shaft 8, which is operated from a horizontal shaft 9. The horizontal shaft 9 carries a gear 10, which meshes with a gear 11 on the rotating carrier of a double-seaming machine. 90

Leading from the lower end of the stackholder is a chute 12, into which the can ends drop as they are released from the stackholder one at a time. This chute is sufficiently wide at its upper end to allow 100

the can end when one edge thereof is released by the rotation of the releasing wheel 7, to swing around into a vertical position, and to drop by gravity into the vertical portion 13 of the chute 12. The vertical portion 13 of the chute 12 leads to a point adjacent the rotating carrier 2, so that the can ends passing through the chute will be delivered to the seaming stations as they 10 pass by the delivering chute for the can ends.

It has been found in practice that where the rotating carrier for the double-seaming machine is driven at high speed, the can 15 ends will not pass through the delivering chute with sufficient rapidity to be carried into the receiving pockets of the seaming stations.

In order to accelerate the travel of the can 20 ends, I have provided a rotating wheel 14, which may be made in the form of a brush, or which may have a rubber contact surface, or which may be made in any other suitable way. This rotating brush is mounted 25 on a shaft 15, which is journaled in a sleeve 16, carried by an arm 17, which is connected to a short shaft 18 freely mounted in a supporting lug or bracket 19 carried by the main frame of the machine. The right 30 hand end of the shaft 15, as viewed in Fig. 4, carries a gear 20, which meshes with a gear 21 loosely mounted on the shaft 18.

A belt wheel 22 is attached to the gear 21. This belt wheel rotates the gear 21, which in 35 turn rotates the gear 20, and through the shaft 15 operates the rotating brush 14. The wall of the chute 12 is slotted as at 23, and the rotating wheel 14 is so positioned as to project through the slot and across the 40 path of travel of the can ends in the vertical portion 13 of the chute 12. The arm 17 supporting the sleeve 16, in which the shaft 15 is journaled, is free to turn about the supporting lug or bracket 19 therefor. The 45 wheel 14 rotates in the direction of the arrow shown in Fig. 3.

The gear wheel 21 rotates also in the direction of the arrow indicated in Fig. 3 of the drawings. This rotation of the gear 50 21 would tend to cause the gear 20 to travel bodily about the axis of the gear 21, and as the arm 17 is freely mounted, the wheel 14 will be forced across the chute for the can ends by the force applied to the gear 21, to 55 rotate the same.

In other words, the wheel 14 will be yieldingly forced across the chute for the can ends, and will, therefore, yield to allow a can end to be engaged by the wheel and conveyed along the chute.

The belt wheel 22 is driven by a belt 24, which is given a quarter turn and engages a

corresponding belt wheel on a countershaft 25 carried by a bracket 26. The other end of the countershaft 25 is provided with a 65 belt wheel 27, and a belt 28 coöperating with the belt wheel 27 also engages the belt wheel 29 on the shaft 9 driven from the rotating carrier of the double-seaming machine.

From the above description, it will be apparent that as the carrier rotates, the shaft 9 will drive the releasing wheel 7, and through the countershaft 25 will also drive the rotating wheel or brush 14. As the can ends are released one at a time from the stackholder, 75 they will drop by gravity into the chute 12, and will pass into the vertical portion 13 thereof. As soon as the can ends come into range of the rotating wheel or brush 14, they will be engaged thereby, and as this 80 brush is rotating rapidly, the speed of travel of the can ends will be greatly accelerated, and the can end will be forced into the vertical portion 13 of the chute along which they move to the seaming station of the double-seaming machine. This rotating brush or wheel not only accelerates the travel of the same from the widened portion of the chute 12 into the vertical portion 13 thereof. 90

While I have shown a rotating wheel for engaging and accelerating the travel of the can ends, it is obvious that other devices may be used for this purpose. The essential feature of the invention consists in some 95 positively actuated or moving means which engages the can ends as they are fed by gravity, and accelerates the travel of the same, so that they may be fed with a greater rapidity to the seaming machine than can 100 be accomplished where gravity alone is relied upon as the force for feeding the can ends.

While I have shown my invention as applied to the feeding of can ends to a double-seaming machine, it will be obvious that said invention may be used for feeding other articles than can ends, and that said articles may be fed to any character of operating device, the general purpose of the invention 110 consisting in engaging an article which is delivered by gravity, and accelerating the travel thereof, so that said articles may be fed with greater rapidity to an operating device.

Having thus described my invention, what I claim as new and desire to secure by Letters Patent, is:—

A can end feeding device including in combination, a stack-holder, a chute for conveying the can ends by gravity from the stack-holder to an operating device, one wall of said chute being slotted, a rotating brush disposed so as to project through said slot

and engage the can ends in the chute, a shaft supporting said brush, a sleeve in which said shaft is journaled, a pivoted arm supporting said sleeve, a gear carried by said shaft, and a gear meshing with the gear on the shaft, said gears being so disposed that the rotation of the brush will cause the arm to swing about its pivotal connection

and press said brush yieldingly against the can ends. ¹⁰

In testimony whereof, I affix my signature, in the presence of two witnesses.

A. L. KRONQUEST.
